DESK

Albert E. Rice and Ford A. Rice, both of 945 Leader Bidg., Cleveland, Ohio

Filed Feb. 28, 1962, Ser. No. 69,014

Term of patent 14 years

(Cl. D33—7)

Fig. 1

The side not shown is substantially the same in appearance as the side shown.

We claim:

The ornamental design for a desk as shown and described.
